A. J. FILKINS

EXHAUST HEAD FOR EXHAUST STEAM PIPES

Filed June 10, 1922

Inventor
Arthur J. Filkins.

By Princess Sophie Maria
Altys

UNITED STATES PATENT OFFICE.

ARTHUR J. FILKINS, OF RIVERSIDE, ILLINOIS.

EXHAUST HEAD FOR EXHAUST-STEAM PIPES.

Application filed June 10, 1922. Serial No. 567,477.

To all whom it may concern:

Be it known that I, ARTHUR J. FILKINS, a citizen of the United States, residing at Riverside, in the county of Cook and State of Illinois, have invented certain new and useful Improvements in Exhaust Heads for Exhaust-Steam Pipes, of which the following is a specification.

As is well known, exhaust steam pipes for exhausting the steam from engines and the like, when installed in cities or other closely built localities, are commonly carried upwardly to a point above the roof of the building in which the steam engine is located, and from this point the exhaust steam is expelled with considerable force into the atmosphere in a series of sharp staccato puffs in rapid succession. This results in a spray of minute particles or drops of water accompanied frequently with small globules of lubricant, as oil and the like, being discharged into the atmosphere with the steam, which has the objection of wetting and soiling anything within its path of descent to the street level. This discharge of steam from steam exhaust pipes has proven such a nuisance that cities have found it necessary to pass ordinances prohibiting the discharge of exhaust steam pipes into the atmosphere, unless such pipes are equipped with a suitable trap or exhaust head for muffling and controlling the discharge therefrom.

The primary object of the invention is to provide an improved exhaust head which will so control the exhaust steam as to check the force and muffle or deaden the sound with which the steam is expelled into the atmosphere and cause the steam to rise from the exhaust head in a gradual manner and without force.

A further object of the invention is to provide an exhaust head that will expedite condensation and collect all condensation of steam therewith and direct the water resulting therefrom to a roof gutter, sewer or other point of discharge.

Other objects of the invention will appear from the following description of the preferred form thereof, shown also in the drawing forming a part of the specification, the features of novelty being set forth in the appended claims.

In the said drawing, Fig. 1 is an elevation view, partly in section, of the improved ex-

haust head shown as applied to the upper end of an exhaust steam pipe, the lower portion of the pipe being broken away.

Fig. 2 is a horizontal sectional view taken on line 2—2 of Fig. 1 looking in the direction of the arrows.

Like reference characters designate like parts throughout the drawing.

Reference character 10 indicates the outer casing of the improved exhaust head and has the interiorly screw threaded portion 11 extending downwardly from the bottom thereof for receiving exhaust steam pipe 12 in screw threaded engagement therewith, as at 13. Screw threaded portion 11 extends upwardly into the casing 10 forming an annular wall 14 around the central internally screw threaded opening 15 in the bottom of casing 10, thus forming a gutter or drainway 16, which communicates with drain pipe 17, which has screw threaded engagement with the screw threaded opening 18 adjacent the drainway 16. Drain pipe 17 may communicate with a roof gutter, sewer or any other means for the disposal of waste water and is for the purpose of draining water which is collected in gutter 16 from the condensation of steam within the exhaust head. The wall of the outer casing 10 is thickened at its upper end, as at 19, and is recessed on its inner periphery forming a seat 20 for the reception therein of radial arms 21 on the circular cup like baffle 22. Baffle 22 is suspended within and concentrically with outer casing 10 with its wall spaced from the wall of the outer casing to provide a passageway for the exhaust steam upwardly to cap 23. Cap 23 is formed with an inwardly extending wall which is inclined toward the center, first upwardly as at 24, and then downwardly, as at 25, forming an apex 26. The downwardly inclined wall 25 terminates in a downwardly extending portion or throat 27 which extends into and concentrically with the vertical wall of baffle 22. The cap 23 with its downwardly extending throat 27 thus forms a second and abrupt baffle in the path of the exhaust steam which practically completely checks the force with which the steam is expelled from the outlet of the steam head. The steam is thus caused to rise from the steam head in an approximately uniform flow and with greatly reduced force. Baffle 22 has a concavo-convex bottom 28 and is provided

with an outlet 29 for water collecting in the baffle from the condensation of steam which outlet discharges into the outer casing 10, and from which the water thus collected is 5 carried from the outer casing by pipe 17 to a point of discharge.

Casing 10 has radially extending ears 30, preferably three in number, which ears are bored, the bores being adapted to register 10 with similar bores through ears 31 carried by cap 23 for the reception therethrough of bolts 32 which are adapted to receive thereon screw threaded nuts 33 for securing the assembled parts of the exhaust head in 15 proper relation.

It will be appreciated from the foregoing disclosure that exhaust steam expelled into the exhaust steam pipe from the cylinder of an engine will first come into contact with 20 the bottom 28 of baffle 22 and be given a downward and outward course, and will pass thence upwardly between the outer wall of the baffle cup and the wall of casing 10 into contact with the top cap 23, being thence 25 deflected downwardly around the outer periphery of throat piece 27 and thence upwardly and outwardly through the discharge opening therein, thus greatly reducing the force and rapidity with which the 30 exhaust steam leaves the cylinder head. At the same time particles of oil or condensed steam will be entrapped and drained through the drain pipe 17.

In order that the invention might be 35 understood I have shown the details of the embodiment of the invention that has been found most successful and that is preferred by me, but it is not desired to be limited to the details of the invention except as defined 40 in the claims, since it will be apparent that persons skilled in the art may resort to various modifications without departing from the purpose and spirit of my invention.

I claim:

45 1. An exhaust head having an outer casing, a baffle suspended therein and concentrically therewith, the baffle having a concavo-convex bottom, the wall of the baffle having an outlet therein, radial supporting 50 arms carried by the upper extremity of the baffle, recesses in the upper portion of the casing adapted to receive the outer ends of the radial arms of the baffle therein, a cap affixed to the casing extending upwardly 55 over the wall of the baffle and downwardly within the baffle forming a throat and spaced from the inner wall thereof, and means for

securing the cap, the baffle and the casing in proper assembled relation.

2. An exhaust head having an outer casing, comprising a body portion and a removable cap, a baffle suspended in the casing and concentrically therewith, co-acting means carried by the body portion and cap of the casing for securing the baffle within the casing, the baffle having a concavo-convex bottom, the wall of the baffle having an outlet therein, the wall of the cap of the casing extending upwardly over the wall of the baffle and downwardly within the baffle 65 forming a throat spaced from the inner wall of the baffle, and means for securing the cap, the baffle and the body portion of the casing in proper assembled relation.

3. An exhaust head having an outer casing comprising a body portion having a removable cap, co-acting means carried by the body portion and the cap of the casing for securing the baffle in a fixed position with relation to the interior of the outer casing, the baffle having a concavo-convex bottom, the wall of the baffle having an outlet therein, the wall of the casing extending upwardly over the wall of the baffle and downwardly within the baffle forming a throat 80 spaced from the inner wall of the baffle, and means for securing the cap, the baffle and the body portion of the casing in proper assembled relation.

4. An exhaust head having an outer casing, a cup-like baffle suspended therein and concentrically therewith and spaced from the inner wall of the casing, an arched cap secured to the outer casing and extending over said baffle and having an upwardly inclined wall and a downwardly inclined wall terminating in a vertically disposed throat, arms formed integrally with said baffle and seated in recesses in said casing and means for securing the cap and baffle to said casing.

5. An exhaust head having an outer casing, a cup-like baffle suspended therein and concentrically therewith and spaced from the inner wall of the casing, an arched cap secured to the outer casing and extending over said baffle and having an upwardly inclined wall and a downwardly inclined wall terminating in a vertically disposed throat, and common means for securing the cap and baffle to said casing.

In testimony whereof I have signed my name to this specification on this 8th day of June, A. D. 1922.

ARTHUR J. FILKINS.
